UNITED STATES PATENT OFFICE.

FRANK MAURER, OF SEKITAN, OHIO, ASSIGNOR OF ONE-HALF TO DENNIS E. GLEASON, OF NORTH BEND, OHIO.

COMBINATION ROLLER AND BRUSHING DEVICE.

Application filed May 25, 1926. Serial No. 111,576.

The present invention relates to a combined rolling and brushing device for use by paper hangers and bill posters or the like.

- 5 An important object of the invention resides in the provision of a contrivance of this nature which embodies all the features of a roller and a brush so that both operations may be accomplished simultaneously.
- 10 A still further very important object of the invention resides in the provision of a device of this nature, which is exceedingly simple in its construction, inexpensive to manufacture, easy to manipulate, reliable
- 15 and efficient in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

25 In the drawing:—

Figure 1 is a plan view of the contrivance embodying the features of my invention, and

30 Fig. 2 is a longitudinal section therethrough.

Referring to the drawing in detail, it will be seen that the frame F of this contrivance includes a U-shaped member 5 having plates 6 fixed to its sides as at 7. These plates 6 are provided with laterally extending legs 8 at their extremities. Rollers 9 and 10 are journaled in the legs 8. A brush head 11 is provided with ears 12 pivoted to the plates 6 between the member 5 and the roller 10 and includes bristles 13 projecting in close proximity to the roller 10. A handle 14 has a pair of brackets 15 fixed to its end as at 16. These brackets are substantially L-shaped in formation, and their extremities are rotatable on a bolt 17 extended through the sides of the member 5 and adjacent portions of the plates 6.

A pair of rods 18 are attached to the brackets 15 adjacent the handle 14, and are pivotally engaged with the brush head as at 19 so that by swinging the handle, the angle of the bristles 13 to the surface over which the contrivance is being moved may be varied as desired. The brackets 15 are connected by cross brace 20.

In using this contrivance, the handle 14 will be disposed as shown in Fig. 2, when the contrivance is being moved upwardly to apply paper or a poster to a wall or the like, but as the contrivance is moved downwardly, the handle 14 would be swung inwardly, that is, in a clockwise direction referring to Fig. 2, so as to change the angle of the bristles 13, so that they will brush in the desirable manner, as will be apparent.

It is thought that the construction, operation, utility and advantages of this invention will now be clearly understood without a more detailed description thereof. The present embodiment of the invention has been disclosed in detail merely by way of example, since in actual practice, it attains the features of advantage enumerated as desirable in the statement of the invention and the above description. It will be apparent that numerous changes in the details of construction, and in the combination and arrangement of parts may be resorted to without departing from the spirit or scope of the invention as hereinafter claimed, or sacrificing any of its advantages.

Having thus described my invention, what I claim as new is:—

1. A device of the class described including, in combination, a U-shaped member, a pair of sides fixed to the ends of the U-shaped member and having laterally extending legs at their extremities, rollers journaled in the legs, brackets pivotally associated with the sides, a handle in the brackets, a brush pivotally mounted between the sides adjacent one roller, and connecting means between the brackets and the brush whereby the handle may be swung to vary the angle of the brush to the surface over which the rollers are being moved.

2. A device of the class described including, in combination, a frame structure, a roller journaled in the frame structure, a brush pivotally mounted in the frame structure, brackets pivotally mounted on the frame structure, a handle engaged in the brackets, and connecting means between the brackets and the brush whereby the handle may be swung to vary the angle of the brush to the surface over which the roller is being moved.

In testimony whereof I affix my signature.

FRANK MAURER.
